CLOSURE FOR BOTTLES OR THE LIKE

Merrill M. Kistner, Chicago, Ill., assignor to C.
Paul Parker, Evanston, and Chester D. Kern,
Chicago, Ill., jointly

Application April 22, 1937, Serial No. 138,313
Renewed January 19, 1940

6 Claims. (Cl. 215—7)

The invention relates generally to closures for bottles or other containers and more particularly to closures which are especially suitable for use in connection with liquor merchandising packages or the like.

A general aim of the invention is to provide a new and improved closure which is simple and economical to manufacture, may be produced and supplied to the bottler in the form of a unitary structure capable of being quickly assembled on a filled container as said container passes along a production line and which may embody, as an integral part of the unit, a breaker or sealing strip for indicating to a purchaser or user that the container either has or has not been opened since it left the manufacturer or bottler. A closure utilizing the sealing strip may be generally referred to as a "tamper-proof closure."

Another object of the invention is to provide an improved closure which embodies resilient means for exerting a force tending to hold the closure in tightly assembled relation on the container.

In conjunction with the foregoing, another object is to provide in a closure assembly, which includes a screw threaded cap, a part fixed to the container and engageable by the cap and having a yielding resiliency which becomes effective as the cap is seated in sealing relation on the container to exert a force for holding the cap in that position.

Another object of the invention is to provide a novel closure structure for a container which embodies a cap or similar closure for sealing the mouth of the container and which is detachably associated with another part secured to the container.

Still another object of the invention is to provide means for assembling the tamper-proof closure device upon the neck of the container in such a manner that relative rotation between the assembled parts is prevented.

Other objects and advantages will become apparent in the following description and from the accompanying drawing, in which:

Figure 1 is a fragmentary view in perspective of a bottle having thereon a closure assembly embodying the features of the invention.

Fig. 2 is an enlarged view of the neck of a container having a closure assembly thereon, the assembly being shown in axial section and the container partially in axial section.

Fig. 3 is a transverse sectional view taken substantially along the line 3—3 of Fig. 2.

Figs. 4 and 5 are detailed sectional views on an exaggerated scale showing the positions assumed by the parts in the seated and unseated positions of the cap.

While the invention is susceptible of various modifications and alternative constructions, I have shown in the drawing and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

While a closure structure embodying the present invention will be considered and described in the environment of a closure for a liquor container or bottle, it is to be understood that it is equally adaptable for use in other fields. Referring to the drawing, the illustrated form of closure is fashioned for association with the neck 10 of a bottle, which defines the usual filling and pouring opening or mouth 10a. The external surface of the neck, adjacent to the mouth, is smooth and generally cylindrical, as indicated at 11, and this surface terminates at an abrupt, substantially radial shoulder 12 forming one side face of an annular rib 13. The opposite side of the rib, together with a second rib 14 spaced therefrom, defines an annular groove 15. If desired, the peripheral surface of the rib may be provided with a plurality of irregularities such as tapering or inclined ribs or corrugations 16 extending generally in an axis paralleling direction. As may be seen in Fig. 2, the corrugations 16 are preferably of increasing thickness from the outer to the inner ends thereof.

In the present embodiment, as may best be seen in Fig. 2, the closure assembly includes a cap 17 adapted detachably to engage a sleeve 18 which fits about the cylindrical surface 11 and in turn is held permanently on the container by a collar 19 which, in effect, embraces the rib 13. In the tamper-proof form of the closure, a seal indicating member 20 is disposed to extend across the outer face of the cap 17 with the end portions of the strip permanently secured between the sleeve 18 and the collar 19. Preferably these parts are assembled into a permanent unitary structure prior to installation on a container.

The sleeve 18 is dimensioned to fit snugly but slidably about the smooth cylindrical surface 11 of the neck and is provided with screw threads, as shown, for engagement by the complementary screw threads on the cap 17. As may be seen in

Figs. 2, 4 and 5, the height of the sleeve is less than the length of the cylindrical portion 11 so that the outer margin of the sleeve stops or terminates a short distance from the end face 5 of the neck. The opposite end of the sleeve carries an integral, radially outturned flange 21 which generally overlies the side face 12 of the rib 13. The peripheral margin of the flange 21 is straddled by a U-shaped bend or curl 22 on 10 the collar 19, whereby permanently to unite the sleeve and collar. This union may be conveniently formed by a simple spinning operation. The collar, in turn, is permanently affixed to the neck of the container by spinning or otherwise forcing a portion, designated 23, thereof 15 into the groove 15. The collar is formed of relatively heavy tough metal stock and removal thereof without breaking the bottle is exceedingly difficult, if not impossible.

20 The cap 17 is of more or less conventional design and includes a sealing gasket or the like 24 internally seated against the flat top. The seal indicating strip 20 is preferably in the form of an elongated member having a central dish-shaped portion, indicated at 25 (Fig. 1) adapted to fit snugly about the outer face of the cap and having end portions 26 extending along opposite sides of the cap and between the flange 21 on the sleeve and the curl 22 on the collar. The seal indicating strip is, of course, applied after the cap has been screwed onto the sleeve and before the flange and collar are joined. If desired, the seal may be weakened, as indicated at 27, to facilitate 30 rupture of the strip when the cap is first unscrewed.

In assembling the closure unit on a container, the unit is first placed over the end of the neck, after which inward pressure is applied by suitable mechanism marginally to the outstanding shoulder formed by the flange 21 and curl 22. This pressure forces the closure unit inwardly of the neck of the container and effects a tight seal between the gasket and the end face of the neck. While the assembly is held in this condition, 40 the portion 23 of the collar is spun or forced into the groove 15. From a consideration of Fig. 4, it will be seen that the parts are so dimensioned that, when pressure is applied to the outstanding shoulder of the unit, the flange 21 will be sprung outwardly and placed under tension, the sleeve and flange being formed of a material, such as a somewhat resilient metal, which will yield. That is to say, the sleeve assembly is shorter than the neck surface 11 so that, when the gasket and neck end engage, the flange is spaced from and will be sprung toward the shoulder 12 when pressure is applied. Hence, after the assembly of the unit with the container is completed, the cap will be held firmly seated with respect to the mouth of 50 the container by the resilient force of the tensioned flange 21. The container, accordingly, will be tightly sealed regardless of any irregularities of the container structure and will remain sealed under substantially all of the conditions to which the container may be subjected. Moreover, after the cap has once been removed, it may again be screwed onto the sleeve 18 and the final force exerted thereon to seat the gasket against 60 the neck will be effective to slide the sleeve 18 slightly outwardly along the neck and place the flange 21 again under tension. The container, therefore, may be repeatedly opened and closed, yet each time a tight leak-proof seal will be obtained. The closed and opened positions of the

parts are shown on a greatly exaggerated scale in Figs. 4 and 5, respectively.

The peripheral irregularities 16 on the rib 13 are pressed slightly into the collar 19, preferably during the operation of engaging the collar portion 23 with the groove 15. By reason of the increasing thickness of the irregularities 16 toward their inner ends, reception of the collar 19 in engagement therewith is facilitated. This engagement prevents rotation of the closure unit relative to the container neck. It will be evident, however, that relative movement between the closure member and the neck will not be seriously disadvantageous, since the resiliency of the flange 21 will permit the assembly to move as a unit 15 without breaking the sealing engagement between the neck and the gasket. Prevention of rotation does not facilitate manipulation of the cap with one hand.

From the foregoing, it will be understood that 20 a novel unitary closure structure has been provided which possesses many desirable features. It may be manufactured economically and supplied to the bottler or user as a unit adapted to be applied as the bottles pass along a production line. It preserves the original fluid tight seal under tension and may be repeatedly resealed as tightly. Furthermore, all of the parts of the unit, with the exception of the gasket, are out 25 of contact with the container contents, the pour 30 is through glass when the container is a bottle, and there is no possibility of chemical reaction between the closure metal and the contents.

I claim as my invention:

1. A tamper-proof closure for a container having a neck provided with an externally smooth end portion and an annular rib adjoining said smooth portion, comprising a unitary assembly having, in combination, a part dimensioned to fit relatively snugly about said smooth portion and to terminate short of the open end face thereof, an outstanding flange on said part adapted to overlie the side face of said rib next to said smooth portion, a channel-shaped collar adapted to be permanently secured in overlying relation to 45 said rib and having an independent union with said flange, a cap screw threaded onto said part and adapted for sealing engagement with the open end of said neck, and a seal indicating strip 50 extending across said cap and having its end portions irremovably bound between said flange and collar.

2. In a closure comprising a unitary structure adapted to be secured in sealing relation to the neck of a container, the combination of a member adapted to surround the outer end section of said neck and having a lateral flange, means for securing said member in place including a portion providing a groove peripherally surrounding and engaging said flange therein, and a cap carried by said member for sealing engagement with the mouth portion of said neck.

3. In a tamper-proof closure assembly of the character described for a container having an open-mouth neck, in combination, a member dimensioned to surround the outer end section of said neck and having a portion projecting laterally therefrom and including a surface facing generally in the direction of said mouth, a cap screw threaded onto said member, a breaker strip 70 extending across said cap and having its end parts lying against said surface, and means coacting with said surface for clamping said end parts permanently against said surface.

4. In combination in a tamper-proof closure 75

- assembly, a container having an open-mouth neck, an annular rib projecting from said neck spaced from the mouth thereof, a sleeve encircling said neck between said rib and said 5 mouth and having a lateral flange at its inner end extending across and in spaced relation to the adjacent face of said rib, a member engaging said rib and said flange to secure said sleeve in place, a cap engaged upon said sleeve for closing said mouth, and a tamper-proof sealing member engaging said cap and having portions thereof engaged permanently between said flange and said member and arranged to be ruptured in the unscrewing movement of said cap.
- 10 5. A tamper-proof closure comprising, in combination, a sleeve to encircle the neck of a container spaced from the mouth of the latter, a closure cap threaded upon said sleeve, a sealing strip lying across said cap and having the ends thereof extending therebeyond, means for connecting said sleeve to the container neck, means for resiliently joining said sleeve and said connecting means including means for permanently anchoring said strip ends to assure irreparable disruption of the sealing strip upon removal of said cap from said sleeve, said resilient joining 15 means permitting movement of said sleeve longitudinally of the container neck when said cap is drawn up tightly against the mouth of the container neck.
- 15 6. In a tamper-proof closure, the combination with a container neck of a closure therefor, a breaker strip extended across said closure and longitudinally along said neck, and means for permanently affixing the ends of said strip to the assembly, said neck having corrugations extending longitudinally thereof in an axis-parallel direction for relative rotation preventing engagement by said means, said corrugations being of increasing thickness from the outer to the inner ends thereof to facilitate reception of said means. 20
